GAME APPARATUS

Herbert G. Breitenstein, Chicago, Ill., assignor to
Raymond T. Moloney, Chicago, Ill.

Original application March 7, 1934, Serial No.
714,477. Divided and this application August
1, 1934, Serial No. 737,963

5 Claims. (Cl. 194—92)

This invention relates to game apparatus and the present application is a divisional application of my co-pending application S. N. 714,477, filed March 7, 1934 for a Game of skill.

5 In the so-called pin and marble games an inclined play field board is provided having holes through which projected balls are dropped onto a slidably mounted inclined underpanel, said panel being manually slidable by means of a coin release slide or chute. Sliding movement of the panel frees the played balls which have collected at the lower edge thereof to move into a trough that delivers them by gravity to a lifter for projection by a shooter over the play field board.

10 In general practice this coin chute embodies a magnet to hold spurious magnetic coins to lock the slide against an abutment to prevent the full instroke of the slide, such full stroke thereof being necessary to move the slidable panel far enough to cause release of the collected balls. The chute has an extension to abut a post on the sliding panel for moving or shifting the latter. In practice it is found when the magnet picks 15 up the spurious coin to jam the coin slide against its full instroke that if the player is unusually unscrupulous and continues to jingle and push on the coin slide, damage frequently is done to the coin slide. Also when the slide jamming action occurs the extension thereof in engagement with the post on the slidable panel permits the player to jingle the slidable panel by manipulating the slide and at times it is possible to free the collected balls in an unauthorized manner.

20 It is desirable, therefore, to provide a latch mechanism for connecting the coin slide and panel to lock and stabilize these parts under the condition described.

25 The main object of the invention, therefore, is to provide a locking mechanism between the coin slide and slidable under panel when a spurious coin jams the slide to prevent a full instroke thereof and to stabilize the slidable panel.

30 Another object is to provide such latching mechanism which will lock and unlock automatically.

35 Still another object is to provide such means which in no way can interfere with the normal use and play of the game mechanism and the coin released slide therefor.

40 Other important objects will be apparent to those skilled in this art as the disclosure is more fully made.

45 Briefly such important objects may be achieved

in the preferred form of the invention herein to be disclosed, by providing a spring pulled pivoted lever on the sliding under panel, said lever being movable into a position when the panel is slid part way by the coin slide, to lock with the coin slide extension to prevent jiggling of the parts and otherwise stabilize them, all as will presently more fully appear.

5 In the accompanying sheet of drawings:

Figure 1 is a general plan view of the game, 10 the top game board being removed to expose the under slide panel, the coin slide, and the improved lock, or check control mechanism;

Figure 2 is an enlarged detail plan view of the lock mechanism associated with the coin 15 slide and under slidable panel; and,

Figure 3 is an enlarged side view of the structure shown in Figure 2 with parts thereof in section as taken along the line 3—3 of Figure 2, looking in the direction of the arrows.

20 The game is the same as shown and described in the parent application heretofore identified, the same comprising the usual box 10 having the front wall 11 which at one side carries a guide 12 in which is mounted a conventional coin slide 25 or chute 13 extending into the box and having an extension 14 formed near its end with a side notch 15. The guide frame 12 in the usual way carries a magnet 16 which in a well understood manner picks up a spurious magnetic slug or coin 30 to cause the slide 13 to jam and prevent a full instroke thereof.

25 The usual top inclined play board having holes through which played balls drop is not shown. Such played balls drop onto an inclined under panel 17 which is slidably carried on transverse roller rods 18 having their ends guided and carried on strips 19 secured to the side walls of the box 10.

30 The lower edge of this board carries a ball accumulating tray 20 and a loop 21 for setting certain indicator mechanism not herein shown. When the panel 17 is shifted rearwardly, or away from the front wall 11, any balls accumulated on the tray 20 roll off and into a transverse inclined 35 trough 22 formed as part of a ball routing casting 23 mounted on the floor of the box 10 in any usual way.

35 These balls, as is common in this art move toward a ball lifter 24 manually operated by a 40 pusher 25 carried in the front wall of the box. These balls are raised one at a time into projecting position above the top play board for projection thereover by a shooter not shown.

45 The rear end of the shiftable panel 17 carries 50

a bracket 26 slidably moving on a bolt 27 carried in the rear wall of the box. Between this bracket and rear wall is located a spring 28 encircling the bolt 27 as shown. When the panel 17 is slid rearwardly this spring 28 is compressed so that when the panel is released, the said spring 28 is effective to push the panel 17 forwardly to its original, or normal position.

As best appears in Figure 2 the forward edge 10 of the panel 17 in line with the chute extension 14 carries a corner plate 29 on which is mounted a post 30. Adjacent this post 30 is a pivot pin 31 carrying pivotally a right angularly shaped lever 32 having an upstanding boss 33. This lever has a rearward extension beyond its fulcrum to which is connected a pull spring 34 secured at 35 to the plate 29.

The adjacent side wall of the box 10 carries a bracket 36 including a vertical guide wall 37 20 against which the lever 32 rides as the panel 17 moves.

The normal position of all parts is shown in Figure 1. If the coin slide 13 receives a spurious magnetic coin and is then pushed into the box 25 by the player the magnet 16 picks up the slug and jams the slide against its full stroke necessary to shift the panel 17 the required distance to free the balls. When the slide is thus pushed in part way the extension 14 abuts the post 30 and 30 moves the panel 17 sufficiently with the plate 29 and lever 32 to cause the said lever to guide against the part 37 and fold, or pivot the lever away from the adjacent wall of the box, against the pull of the spring 34 to engage the part 33 35 thereof in the slot 15 to interlock the slide 13 and panel 17 positively together to check further movement of the parts and prevent jiggling thereof. This interlocked relationship of the parts appears in Figure 2. Thus the panel 17 40 is stabilized and it is impossible to free any balls in any unauthorized manner. All that can be thereafter done by the player is to free the slide 13 to let it be pulled forwardly by the usual coin slide retractor spring, not shown, and at the 45 same time the spring 28 returns the panel 17 to its normal forward position. As these parts return the spring 34 pulls the lever 32 back to the position shown in Figure 1.

When an authentic coin is played in the slide 50 the magnet is inoperative and a full stroke of the slide and its extension 14 is permitted. Such full stroke of course, again causes the lever part 33 to interlock with the extension notch 15. However, the end of the extension 15 continues to push 55 against the post 30 to move the panel 17. At this time the lever 32 merely interlocks to positively connect the slide 13 and panel 17, the lever 32 folding to its longitudinal position and guiding alongside the part 37. When the panel 17 is 60 pushed rearwardly or away from the front wall 11 the lever 32 cannot leave the guide 37 as the latter is long enough to prevent such occurrence.

This improved interlock also has another important advantage in that type of game having 65 play board holes provided with trap doors that are opened by the shifter panel 17. The interlock in such case prevents jiggling of the slide 13 and shifting of the panel 17 when the slide is used in an unauthorized manner.

70 From this disclosure it will now be seen that an improved safety mechanism has been provided which is simple and fool proof in use,

It is the intention to cover herein all changes and modifications of the preferred example illustrated which do not in material respects depart from the spirit and scope of the invention as claimed.

What is claimed is:

1. A game comprising a box and carrying a slidable panel, a coin slide to move the panel, said slide being of the type that jams to prevent a full stroke thereof when a magnetic coin substitute is used therein and having an extension, a post on the panel to be engaged by the extension when moving the panel, a pivotally mounted lever on the panel having means to interlock with the extension when the slide has jammed and moved only part of its stroke, and guide means to interengage said parts as the panel moves.

2. A game comprising a slidably mounted panel, a coin slide to move the panel, said slide being of the type that jams to prevent a full stroke thereof when a magnetic coin substitute is used therein, a lock mechanism to hold the panel against movement when the coin slide jams, said lock comprising a spring pulled pivoted lever carried on the panel and having a boss, said coin slide having an extension provided with a slot to be engaged by said boss for locking the coin slide and panel together, and guide means for governing the movement of the pivoted lever.

3. A game embodying a slidable panel and a coin released slide for sliding the panel, said coin slide being of the type having means to cause it to jam before it can complete its full stroke when a magnetic coin substitute is used in the slide, a pivotally mounted member carried by the panel and having means adapted to cooperate with means on the coin slide to stabilize the panel and prevent jiggling of the latter by manipulation of the coin slide after the latter has jammed, and stationary guide means adjacent the panel to cause the pivotally mounted member to operate as stated.

4. A game embodying a cabinet enclosing a slidable panel and carrying a coin released slide to slide the panel, said coin slide being of the type having means to cause it to jam before it can complete its full stroke when a magnetic coin substitute is used in the slide, a pivotally mounted member carried by the panel and having an upstanding boss adapted to engage a notch in an extension piece carried by the slide whereby to interlock the slide and panel to stabilize the panel and prevent jiggling thereof by manipulation of the coin slide when the latter has jammed, and a guide member for the pivoted member carried by the cabinet adjacent said pivoted member.

5. A game embodying a cabinet having a front wall and a side wall enclosing a slidably mounted panel operated by a coin chute of the type which jams before it makes a complete stroke when a magnetic coin substitute is employed therein, said panel carrying a spring pulled pivoted lock member adjacent the side wall and an edge of the panel in substantial alinement with the coin chute, a guide member carried by the side wall in a position to be engaged by the pivoted lock member when the panel is slid, and interengaging means between the coin chute and lock member to stabilize the panel and prevent jiggling thereof by manipulation of the coin chute when the latter has jammed.

HERBERT G. BREITENSTEIN.
